UNITED STATES PATENT OFFICE.

HERMANN LEHMANN, OF OFFENBACH-ON-THE MAIN, PRUSSIA, GERMANY.

ADJUSTABLE CLASP FOR ALBUMS.

SPECIFICATION forming part of Letters Patent No. 361,766, dated April 26, 1887.

Application filed December 27, 1886. Serial No. 223,592. (No model.)

To all whom it may concern:

Be it known that I, HERMANN LEHMANN, a subject of the King of Prussia, German Emperor, and a resident of Offenbach-on-the-5 Main, in the Kingdom of Prussia, German Empire, have invented new and useful Improvements in an Adjustable Clasp for Albums, of which the following is a specification.

Adjustable clasps which may closely shut 10 big albums as well as thin ones, or an album when it is filled with photographs, or when it is not filled, are well known; but it is very difficult to obtain as fine and as manifold an adjustment of the sliding shutter as is necessary. To obtain such fine adjustment of the 15 clasp is the object of my improvements.

The improvements by which this end is obtained consist in the combination of a coarsely-scaled rack with two catches, the teeth of 20 which stand in different positions relatively to the rack. The two catches engage with the same rack. A fastening of this kind is represented in the drawings.

Figures 1 and 4 are vertical sections through 25 the line *e f*; but the section is only made through the adjustable sliding shutter *S* and its tube *t'*. The other part of the clasp (the box *b*) is shown in this figure by side view. Fig. 2 is a horizontal section, *a b*, of Fig. 1. Fig. 30 3 is a vertical cross-section, *c d*, showing the way in which the clasp is secured to the cover of the album. Fig. 5 is a side view of Fig. 3.

Similar letters refer to similar parts throughout the several views.

35 The angular metal pieces *w* and *w'* are fastened to the side edges of the two covers *d* and *d'*. The angular piece *w'* is provided with the clasp-knob *h*, and on the angular piece *w* are the two attachment-hinges *l* and *l'*. In these 40 hinges *l* and *l'* is a rotating tubular piece, *r*, to which the box *b*, Figs. 2, 3, is fastened. The tubular piece *r* contains the movable tubular piece *r'*. The tubular piece *r'* is always pressed outward by a spiral spring, *s*, and provided 45 with the pressing-knob *n*. For the sake of symmetry, a similar non-acting or dummy pressing-knob, *n'*, is fastened to the attachment-hinge *l*.

The sliding shutter *S* may be moved in the 50 box *b*, and is provided with a hole, *o*, into

which the clasp-knob *h* is put on shutting the album, Fig. 3. The sliding shutter *S* bears the rack *z* and the two tubes *t t*. These spring-cases *t t*, together with the sliding shutter *S*, are always pressed upward by the spiral 55 springs *s s*.

t t are guide-pins. On the box *b* are two or more catch-levers, *q* and *q'*, which may oscillate round the pin *x*. The catch-levers *q q'* are set against each other in such a way that the 60 teeth of them stand in different positions. The difference is equal to about half the distance between the teeth of the rack *z*. The free ends of the catch-levers *q q'* are guided by a slit, *i*, of the tubular pieces *r* and *r'*. 65

It is evident that in the place of two, three and even more catch-levers can be used for the purpose of adjusting the sliding shutter *S* finer and finer and at shorter intervals.

The way in which the sliding shutter is adjusted is as follows: By pressing on the knob *n* the tubular piece *r'* is shoved into the tubular piece *r*. The latter presses with the point *i* against the catch-levers *q q'*, by which means the catch-levers *q q'* are forced out of the teeth 75 of the rack. The springs *s s* then press the sliding shutter *S* upward, and the shutter obtains a position adapted to large albums. If I wish to shut the album more tightly, I press the sliding shutter *S* down and at the same time the 80 knob *n*. Now, I am able to move the shutter *S* against the box *b* as much as the album permits it, and one of the pawls *q* or *q'* will then hold the shutter by means of the rack *z*. By the double pawls *q* or *q'* I may change the position 85 of the shutter by the length of half a tooth of the rack, because then the other pawl gears into the rack *z*.

It is evident that by using two catch-levers, *q* and *q'*, with their pawls set apart, as above 90 mentioned, the adjusting of the sliding shutter *S* is finer than by using only one pawl. I may choose a very coarse pitch of the rack *z*, so that the shutter is fixed very surely by the big pitch, and I may apply two or more pawls gearing 95 into the rack in such a way that the teeth of these pawls lie in different positions relative to the rack.

The fastening or clasp just described can be used for all books, the thickness of which in- 100

creases in time by the things put into them, as is in particular the case with photo-albums, stamp-albums, and similar collection-books.

What I claim, and desire to secure by Letters Patent of the United States, is—

1. In an album-clasp, the combination of a rack, z , with two or more catch-levers, q and q' , having each a pawl placed at unequal distances from their ends, one of these elements (the two pawls or the rack) being attached to the sliding shutter S , the other being attached to the box b , for the purpose of adjusting the clasp as finely as possible.
2. The combination of the sliding shutter S ,

provided with the spring-cases tt and the rack z , with the alternatively-working catch-levers q and q' , the oscillating tubular piece r , and the movable tubular piece r' , contained in it, so that by pressing on knob n the pawl q q' may be forced out of the teeth of the rack z , for the purpose as described.

In witness whereof I have hereunto set my hand in presence of two witnesses.

HERMANN LEHMANN.
